UNITED STATES PATENT OFFICE.

JOHN D. BOWNE, OF NEW YORK, N. Y., ASSIGNOR OF ONE-HALF TO
JAMES MONROE GRAHAM, OF NEW YORK, N. Y.

STEAM WATER-HEATER TEMPERATURE-REGULATOR.

No. 827,608.

Specification of Letters Patent.

Patented July 31, 1906.

Application filed June 15, 1905. Serial No. 265,402.

To all whom it may concern:

Be it known that I, JOHN D. BOWNE, a citizen of the United States, residing at New York, in the county of New York and State of New York, have invented certain new and useful Improvements in Steam Water-Heater Temperature-Regulators, of which the following is a specification.

My invention relates to steam water-heater temperature-regulators—that is to say, it belongs to the same class with apparatus designed to control the supply of steam passing into a water-heater by means of the temperature of the water that has been heated by the steam.

The object of my invention is the production of a regulating contrivance of the character outlined having a special construction and arrangement of elements believed to insure increased effectiveness and economy in operation.

I attain the object sought by fashioning and associating the parts illustrated in the accompanying drawings, of which—

Figure 1 represents a vertical sectional front view. Fig. 2 is a side view, and Fig. 3 is a horizontal section upon the line X X of Fig. 1.

Like numbers are used to refer to the same parts throughout.

Upon the flanged bowl 1, which is provided with the pipe-coupling inlet 2 and outlet 3, to which the water-pipes are connected, rests a hollow cap or cover 4, that is constructed with the internal cavity 5 and a flange usually coextensive with that of the bowl. The bottom of the cavity 6 is pierced by a number of threaded orifices 7, and into those orifices are screwed the open ends of the tubes 8, which thus extend downwardly into the bowl and have their lower ends closed, as shown in Fig. 1. The top of the cavity 5 is provided with a single duct 9, bored upwardly and axially through the central raised portion 10 of the cover 4 and communicating with the pair of diaphragmatic expandible chambers 11, secured to the cover 4 one above the other and opening into each other. The depending tubes 8, the cavity 5, with duct 9 and expandible chambers 11, are all filled with an expansible fluid 12, which may be introduced by way of the stop-cock 13.

Valve-rod 14 is secured to the uppermost chamber 11 and rises and falls with the ex-

pansion and contraction of the two chambers 11. Rod 14 is secured to the lower wall of the underlying member of a second pair of diaphragmatic expandible chambers 15, arranged one upon the other, and the rod passes upwardly through both chambers and by way of the passage 16 in the head 17 of the U-frame 18 enters the valve-chamber 19, formed upon the top of the U-frame. The frame is erected upon the cover 4. (See Figs. 1 and 2.) It will be noted here that the expandible chambers 15, through which the valve-rod passes, take the place of a stuffing-box and effectually and permanently guard against leakage at that point and avoid the necessity for any attention. My purpose in employing two pairs of chambers 11 and 15 is obviously to take advantage of the combined expansion or contraction of the pairs to afford sufficient movement for the valve-rod without unduly increasing the diameter of the chambers.

Valves 20 are suitably secured upon the rod 14 and are provided with the seats 21 in the chambered casting 22, which projects into the valve-chamber and is supplied with the pipe-coupling inlet 23.

The valve-chamber is furnished with a pipe-coupling outlet 24 and has a screw-plug 25 in its top, possessing a suitable channel 26 to receive and guide the upper squared end 27 of rod 14.

In the operation any number of the dependent tubes 8 can be employed. (See Fig. 3.) One or more of them may be omitted and the threaded orifice 7 temporarily closed by the screw-plug 28. It is thought to be clear that the greater number of tubes 8 introduced and filled with the expansible liquid 12 the greater the body of fluid undergoing expansion and the greater and more rapid will be the movement of the valve-rod. The inlet and outlet of the valve-chamber are connected, respectively, to the source of steam and to the heater. As previously explained, the bowl 1 is connected with the hot-water reservoir in the heater. Should the temperature of the water rise beyond a set degree, the expansion of chambers 11 will close the valves and shut off the steam, which is again permitted to flow as the water passing through bowl 1 becomes cooler and the fluid in the chambers contracts. In Figs. 1 and 2 the position of my invention as illustrated is with

the valve-chamber uppermost. That attitude is by no means essential to the operation as described. It will operate equally well when inverted, and its position is always reversed when it is employed as a steam-trap, for which it is peculiarly adapted.

Having thus described my invention, and explained the mode of its operation, what I claim is—

1. In a steam water-heater temperature-regulator, the combination with the bowl having an inlet and outlet, of a cover for the bowl having a cavity and a plurality of orifices through the bottom of the cover and opening 15 into the cavity, tubes having one end closed and extending into the bowl, the open ends of a number of said tubes being removably secured in a like number of the orifices, means for closing the remaining orifices, expandible 20 chambers in communication with the cavity of the cover, a valve-rod attached to and actuated by the movement of said chambers, a valve-chamber, expandible chambers having one wall attached to the said rod and another 25 wall attached to the said valve-chamber, the said rod arranged to pass through the said expandible chambers into the valve-chamber, and valve devices within the valve-chamber controlled by the rod.
2. In a steam water-heater temperature-regulator, the combination with a bowl having an inlet and outlet, of a cover for the bowl having a cavity and a plurality of orifices through the bottom of the cover, tubes 30

having one end closed and extending into the 35 said bowl, the open ends of said tubes being secured in a number of said orifices in the cover of the said bowl, means for closing the remaining orifices, expandible chambers in communication with the cavity of said cover, 40 a valve-rod attached to the said expandible chambers, a valve-chamber having an inlet and outlet, the said valve-rod arranged to enter the valve-chamber, and valve devices operated by the rod and controlling the entrance of steam into the valve-chamber in correspondence with the movement of the said expandible chambers.

3. In a temperature-regulator for a steam-heater, the combination with a body having 50 a cavity, the bottom of the body being pierced with a series of orifices, tubes having one end closed, the open ends of said removable tubes being secured in a number of said orifices, means for closing the remaining orifices, expandible chambers in communication with the cavity of said body, a valve-chamber, valve devices within the said valve-chamber and connections whereby the movement of the expandible chambers is communicated to the said valve devices.

In testimony whereof I affix my signature in presence of two witnesses.

JOHN D. BOWNE.
